UNITED STATES PATENT OFFICE.

JOHN B. MARTIN, OF SHREVEPORT, LOUISIANA.

ELEVATOR FOR SUCKER RODS.

Application filed February 16, 1924. Serial No. 693,254.

To all whom it may concern:

Be it known that I, JOHN B. MARTIN, a citizen of the United States, residing at Shreveport, in the parish of Caddo and 5 State of Louisiana, have invented certain new and useful Improvements in an Elevator for Sucker Rods, of which the following is a specification.

This invention relates to an improved 10 elevator adapted to be used in supporting and coupling of the conventional sucker rod of well drilling equipment to a cable or other elevating mechanism.

A further and important object of this 15 invention is the provision of an elevator for well drilling equipment which may be quickly and conveniently attached to the sucker rod to safely hold the latter against liability of accidental disconnection.

20 Other objects and advantages of this invention will be apparent during the course of the following detailed description.

In the accompanying drawings, forming a part of this specification, and wherein 25 similar reference characters designate corresponding parts throughout the several views,

Figure 1 is a side elevation showing the 30 improved elevator as used for supporting a sucker rod.

Fig. 2 is a plan view of the improved sucker rod, elevator showing the same open incidental to receiving a sucker rod therein.

Fig. 3 is a plan view, partly in cross section, showing cooperating details of the 35 improved elevator with a portion of the body construction thereof removed, this view showing the manner in which the improved elevator is used for connecting a sucker rod thereto.

Fig. 4 is a plan view, partly in cross section, showing the same details as illustrated in Figure 3, however, with the parts in an 40 open relation either for releasing or receiving a sucker rod.

Figs. 5, 6, 7 and 8 are views illustrating 45 details of the improved elevator, and

Fig. 9 is a perspective view of a novel 50 type of pawl or latch device used with this elevator.

In the drawings, wherein for the purpose of illustration is shown only the preferred embodiment of this invention, the letter A

may generally designate the complete elevator which is adapted to be used for supporting a sucker rod B.

The elevator A may consist of the body construction 10 within which is positioned a movable sucker rod coupling member 11. A latch device 12 is preferably provided for securing the member 11 in a desired position within the body construction 10. A bail 13 may be provided in conventional pivoted manner with respect to the elevator body construction 10, and a swivel 14 provided 60 upon the upper end of this bail 13.

The sucker rod B at its upper end is provided with the conventional attaching portion 20 which is reduced intermediate its ends to provide the polygonal portion 21 70 which is received within the elevator device A; the shoulders 22 and 23 at opposite ends of the reduced portion 21 preventing disconnection of the elevator with respect to the attaching portion 20, as can readily 75 be understood by those skilled in the art to which this invention relates.

The elevator body construction 10 preferably includes a body portion or block 25 which is preferably formed of metal and 80 may be polygonal in formation, a desirable arrangement being that of making the same in the shape of an octagon. It is provided with a central opening 26 of relatively large area, and has a radial slot 27 extending 85 from one side edge 28 into the opening 26 and thru which slot 27 the reduced portion 21 of the sucker rod B is slid. A segmental flange 29 extends into the opening 26; this flange being of course, integral with the 90 body 25 and of less thickness than the body 25, and provided for the purpose of slidably supporting the coupling member or disc 11 when the latter is placed within the opening 26. It is to be noted that the segmental 95 flange 29 provides a reduced opening 30^a axially aligning with the opening 26, and with which opening 30 the slot 27 also communicates. Extending upwardly from the top surface of the flange 29 and at a point 100 diametrically opposed to the radial slot 27 a shoulder or lug 31 is provided for the purpose of limiting the amplitude of oscillation or rotary movement of the member 11, and as will be subsequently described.

The rod connecting member 11 is prefer-

ably of metal and of disc shaped formation, including the portion 30 which rests directly in the opening 26, and the portion 31 centrally depending from the portion 30 which is disposed in snug sliding relation within the opening 30^a provided by the flange 29 of the main body 25. A radial slot 33 extends through the portions 30 and 31 to the center of the member 11; the slot at the central portion of this member being polygonal in formation and adapted to receive the polygonal portion 21 of the sucker rod therein in such relation that the sucker rod cannot move axially out of the member, but must be moved through the slot 33 in a radial manner. The slot 33 may be of different dimensions, since sucker rods vary in size, and as is illustrated in Figures 3 and 4 several shapes of slots may be provided. The lower surface 35 of the portion 30 of member 11 slidably rests on the inside surface of the main body flange 29. This surface 35 of the portion 30, however, has a groove or recess 37 upwardly formed therein for one-quarter of a circumference, and which receives therein the projecting lug or portion 31 of the main body 25 of the elevator; vertical shoulders 38 being provided at the ends of this slot 37 against which the sides of the lug 31 may contact to limit the amplitude of oscillating movement of the member 11 when it is disposed within the pocket 26 of the body construction.

35 The portion 25 of the body construction 10 preferably has a tangential recess 40 formed inwardly of the top surface thereof, within which is slidably positioned the latch construction 12. When the member 11 is properly positioned within the opening of the body portion 25 the top surface of the portion 30 of this member 11 lies flush with the top surface of the main body 25 of the construction 10. Thus, to prevent accidental axial movement of the member 11 out of the body construction 25, a cover plate 43 is provided, which is attached over the top surfaces of the main body portion 25 and the member 11; this plate 43 being so attached by means of screws 44 or other detachable elements, and the same having a suitable central opening and a radial slot which aligns with the opening and slot of the body 25.

55 The latch device 12 preferably consists of an L-shaped dog member 50 having an enlarged head 51 slidable in the recess 40 provided in the main body block 25, and includes the L-shaped handle 52 which extends exteriorly of the body for manual operation. A spiral spring 53 is also located in the recess 40 and acts against the head 51 for forcing the same into engagement with the annular edge of the portion 30 of the member 11. Inwardly of this

annular edge of the portion 30 a slot 55 is provided into which the spring 53 forces the dog head 51 to hold the disc or member 11 in a desired relation with respect to the body construction 10, to lock the sucker rod B in a coupled relation with respect to the elevator A, and as is illustrated in Figure 3 of the drawings.

70 The bail 13 is of ordinary construction, including the side arms 60 and 61^a the lower ends of which are apertured for pivotally receiving the lugs 61 which are formed integral with the body 25 of the elevator extend radially of the body from opposite sides thereof. The upper portion 64^b of the bail construction 13 is of a cylindrical shape and terminates in a reduced screw threaded shank 65 adapted to receive a nut 66. The nut 66 is used for securing the 75 swivel attachment 14 to the bail device 13. This swivel attachment 14 consists of the link 68^c which fits loosely upon the shank 65 of the bail and is held thereon by means of the nut 66; suitable ball bearing races 67 being provided between the swivel attachment and nut to permit the swivel attachment to rotate in an anti-friction manner upon the bail.

80 Referring to the manner of operation of the elevator, when it is desired to place an elevator A over the coupling rod B, the coupling member 11 is swung until the radial slots 27 and 33 are in alignment, and the device can then be slipped over the polygonal reduced portion 21 of the sucker rod B, 100 as can readily be understood. When this portion 21 is received at the extreme inner polygonal end of the recess 33 it is merely necessary for the operator to swing the body construction 10 to the left and the radial slot 105 27 of the body portion 25 will move out of alignment with the radial slot of the member 11 and thus lock the sucker rod in the inner end of the slot 33. The shoulders 38 110 contacting against the lug 31 define the limits of movement of the body construction with respect to the member 11, and when the body construction 10 has been moved to the left for its maximum distance the spring 115 53 will throw the dog head 51 into the slot 120 55 and lock the body construction and the member 11 together so that they may not become accidentally detached for releasing the sucker rod. The cover cap or plate 43 is, 125 of course, provided so that different members 11 may from time to time be placed in the opening 26 according to the cross section of the portion 21 of the sucker rod which it is desired that the elevator shall be coupled upon. To release the sucker rod it is merely necessary for the operator to pull the dog 130 50 outwardly from the elevator device A, to compress its spring 53, so that the body construction 10 may be swung relative to the coupling block 11, until the slots 27 and 33

130

are in alignment, and the elevator device A may then be swung off the sucker rod B, as is obvious.

From the foregoing description it is apparent that a very simple and economical type of elevator has been provided which may be conveniently attached or detached with respect to a sucker rod and which is absolutely safe as applied thereto.

10 Various changes in the shape, size, and arrangement of parts may be made to the form of the invention herein shown and described, without departing from the spirit of this invention or the scope of the claims.

15 I claim:

1. An elevator of the class described comprising a body having an opening therein and a radial slot leading to said opening, said body being recessed from its upper face about the opening to provide an annular seat, a lug extending upwardly from said seat, a circular block rotatably fitting into the opening of said body and having a radial slot, said block having an outstanding annular shoulder extending into the recess and resting upon said seat with its upper face flush with the upper face of the body, a cover plate carried by said body and extending over said block to retain the same in place and permit rotary movement thereof so that a portion of the slot of said member extends into the area of the opening of said body, said block being turnable within said body so that the slots of the block and body may be placed in alignment or out of alignment with respect to each other, the annular shoulder of said block having its inner face provided with an annular recess receiving said lug and limiting rotary movement of said block and latch means for holding the block in a locked relation with respect to the body when the slots are out of alignment with respect to each other.

2. An elevator of the class described comprising a body having an opening therein and a radial slot leading to said opening, said body having a flange segmentally extending into said opening, a member rotatably mounted in the body and resting on said flange and having its flange engaging face provided with a circumferentially disposed recess having abutment shoulders at its ends, said member having a radial slot therein, a lug extending from said flange into the recess of said member to limit rotation thereof and means securing the member in the opening of said body for rotation therein to permit said slots to be placed in alignment or out of alignment with respect to each other, the slot of said member being so related to the slot and opening of the body that when the slots are out of alignment

with each other a portion of the inner end of the slot of said member will be exposed through the opening of said body.

3. In an elevator of the class described the combination of a body portion providing a central opening therein with a radial slot leading to said central opening from an edge of said body, an annular flange integrally formed with the body extending into the area of said opening in a non-obstructing relation with respect to the said slot, a lug formed upwardly on said flange extending into said opening, a member having a slot radially therein, means securing the member in the opening of said body resting upon said flange, said member having a groove therein adapted to receive the lug of said body to limit the amplitude of movement of said member within said body whereby the slot of said member may be placed in alignment with the slot of said body or moved out of communication with the slot of said body, the inner end of the slot of said member extending into the area of the opening of said body and adapted to receive therein a portion of a rod for coupling the same to said elevator when the member is so positioned in said body as to have its slot out of aligning relation with respect to the slot of said body.

4. In an elevator of the class described the combination of a body portion providing a central opening therein with a radial slot leading to said central opening from an edge of said body, an annular flange integrally formed with the body extending into the area of said opening in a non-obstructing relation with respect to the said slot, a lug formed upwardly on said flange extending into said opening, a member having a slot radially therein, means securing the member in the opening of said body resting upon said flange, said member having a groove therein adapted to receive the lug of said body to limit the amplitude of movement of said member within said body whereby the slot of said member may be placed in alignment with the slot of said body or moved out of communication with the slot of said body, the inner end of the slot of said member extending into the area of the opening of said body being adapted to receive therein a portion of a rod for coupling the same to said elevator when the member is so positioned in said body as to have its slot out of aligning relation with respect to the slot of said body, and a latch mechanism adapted to lock the member to said body when the slots are out of communicating relation with respect to each other.

JOHN B. MARTIN.
